CLAIM

The ornamental design for plastic-projecting molding machine, as shown and described.

DESCRIPTION

FIG. 1 is a top, front and left side perspective view of a plastic-projecting molding machine showing my new design;

FIG. 2 is a front elevational view;

FIG. 3 is a rear elevational view;

FIG. 4 is a left side elevational view;

FIG. 5 is a right side elevational view; and,

FIG. 6 is a top plan view thereof, the bottom plan view being plain and unadorned.

FIG. 1 has been drawn on an enlarged scale with respect to FIGS. 2-6.

FIG. I

FIG. 2

FIG. 3

FIG. 4

FIG. 5

FIG. 6
